UNITED STATES PATENT OFFICE.

MATTHÄUS KLINGLER, OF OBERNDORF-ON-THE-NECKAR, GERMANY, ASSIGNOR TO WAF-FENFABRIK MAUSER AKTIENGESELLSCHAFT, OF OBERNDORF-ON-THE-NECKAR, GERMANY.

SIGHTING APPARATUS FOR FIREARMS.

No. 904,880.

Specification of Letters Patent.

Patented Nov. 24, 1908.

Application filed January 30, 1906. Serial No. 293,625.

To all whom it may concern:

Be it known that I, MATTHÄUS KLINGLER, mechanic, a subject of the King of Württemberg, residing at Oberndorf-on-the-Neckar, in the Kingdom of Württemberg, Germany, have invented certain new and useful Improvements Relating to Improved Sighting Apparatus for Firearms, of which the following is a full, clear, and exact description.

The present invention relates to pivoted or rising sights of that type which are hinged upon the top of the sight bed, and in which the curved leaf of the sight is erected either positively by means of a slide, or by spring pressure from above or below, and in which the adjustment of the leaf has hitherto been effected by the slide through a curved guide in the form of lateral projections or ribs carried by the leaf for the purpose of enabling the sighting scale to be equally divided. Heretofore such plungers have been arranged one on each side of the sight and moved in opposite directions.

The characteristic feature of the improvements, to which this invention relates, consists in the fact that for the purpose of enabling the adjustment to be effected directly, that is to say, without the intervention of a separate curved guide, while at the same time employing an equally divided scale, the leaf of the sight has itself the form of a single curved plate that is free from cross pieces or ribs, and bears upon its face the equally divided scale. Moreover, in the sight in accordance with this invention, the arrangement is such that two readings can be determined by means of each notch; this being effected by so arranging the plungers whereby the slide is held that they lie side by side, and move in the same direction, so that the movement of the slide from one to the other of the marks corresponding to two successive readings, can be effected by pressure exerted from the one side.

The accompanying drawing illustrates a sighting apparatus made in accordance with this invention; Figure 1 being a longitudinal section, Fig. 2 a transverse section; Fig. 3 a plan; Fig. 4 a partial underside view and Fig. 5 a side elevation of the apparatus, showing its sight adjusted to a certain range.

The sight consists, as usual, of the tubular bed *a* mounted on the barrel or the like, the leaf *b*, and the slide *c*. In the example shown, the leaf *b* is formed as a plate of uni-

form thickness the sides of which are embraced by the slide *c*. This leaf *b* is provided with a graduated scale and it is so curved as to enable this scale to be graduated in equal or at all events approximately equal distances. The projections *d* upon the slide *c* which project inwardly over the longitudinal edges of the leaf *b* are each tapered to a knife edge so as to serve as indicators for the sighting scale.

The slide *c* has the usual rectilineal movement over the bed *a* and is secured in position by means of plungers which engage in notches provided upon the edge of the bed *a*. In the example shown the plungers *e* and *f*, which are, as usual, spring-actuated, lie side by side (Figs. 2, 4 and 5) and are respectively provided with detents *g* and *h* which, actuated by the springs pertaining to the said plungers, alternately and automatically engage with the notches *a'* provided in the bed *a*. These notches are so arranged in relation to the detents *g* and *h* of the plungers that one or the other detent comes into engagement with a notch *a'* whenever the slide is moved upon the graduated scale through a distance corresponding to 50 meters.

The release of the plunger for the time being in engagement is effected by pressing upon the head thereof; the arrangement being such that the release of either plunger can be effected from the same side by simply pressing inwardly the head of that plunger *e* or *f* which happens at the time to project outwardly.

In order to effect the adjustment of the slide from a smaller to a greater range, the heads of both the plungers *e* and *f* must be pressed inwards whereupon the slide *c* can easily be moved over the bed *a* of the sight, and the leaf *b* thereof can be so raised as to come into contact with one or other of its two guiding surfaces; this being effected either positively or by spring pressure exerted from above or below.

What I claim as my invention, and desire to secure by Patent is:

1. A sighting apparatus for fire arms, comprising a slide adapted to move backward and forward along the sight bed, a sighting leaf pivoted at one end and adapted to swing upwardly and downwardly, said leaf comprising a plate of curved form of substantially uniform thickness from side to side.

- side, said plate having a sighting scale substantially uniformly spaced along its upper side, said slide having pointers extending over the top of the plate and adapted to cooperate with said scale, said pointers engaging the upper face of the plate and preventing the latter from moving except in accordance with the movements of said slide.
- 10 2. A sighting apparatus for fire arms, comprising a slide adapted to move rectilinearly along the sight bed, and a sighting leaf adapted to swing upwardly and downwardly, said leaf comprising a plate of curved form, and having a sighting scale substantially uniformly spaced along its upper side, said slide engaging said plate

directly so as to control its adjustment, and means in connection with said scale for determining the position of said plate, a part having a series of notches, and two detents carried by said slide adapted to engage said notches, such detents having actuating parts on the same side of said slide, so that either can be adjusted from such side, and so that two readings can be obtained by means of a single notch.

In witness whereof, I have hereunto signed my name in the presence of two subscribing witnesses.

MATTHÄUS KLINGLER.
